UNITED STATES PATENT OFFICE.

JENNIE KELLEY, OF CHICAGO, ILLINOIS.

ADJUSTABLE WHEELED RECEPTACLE FOR GOLF-CLUBS.

1,231,030.

Specification of Letters Patent. Patented June 26, 1917.

Application filed May 12, 1916. Serial No. 96,979.

To all whom it may concern:

Be it known that I, JENNIE KELLEY, a citizen of the United States, residing at Chicago, in the county of Cook and State of Illinois, have invented certain new and useful Improvements in Adjustable Wheeled Receptacles for Golf-Clubs, of which the following is a specification.

The essential object of this invention is to provide a wheeled receptacle for golf clubs and the like, which receptacle is adapted to be transported from place to place by being pulled along while it rides upon its wheels, thus dispensing with the necessity of carrying a heavy sack containing the clubs. The invention, moreover, provides a receptacle which can be placed in a substantially vertical position with the open end upward, thus permitting the player to select the club required for any particular shot while the container remains in an elevated and therefore readily accessible position.

In the drawings, Figure 1 is a side elevation of the invention when the receptacle is in upright position; Fig. 2 is a bottom plan view looking upwardly from below in Fig. 1; Fig. 3 is a detail upon an enlarged scale as compared with Fig. 1 of the parts at the bottom of the receptacle and looking toward the left or in the direction of the arrow A, Fig. 1; and Fig. 4 is a detail of one of the devices adapted to hold the receptacle in upright or vertical position.

The receptacle 1 within which the clubs are adapted to be contained, is a substantially tubular member adapted to be made of sheet metal, fabric, or any other convenient material. The tube 1 is fastened to a ring or band 2 at the top and to a similar band 40 or ring 3 at the bottom, which members 2 and 3 are preferably made of metal or other relatively non-yielding material. Wheels 4 and 5 are fastened upon the axle 6, which axle is journaled in hubs 7 and 8. The hub 45 7 is secured to the downwardly-depend ing strap or lug 9, and the hub 8 to a similar strap or lug 10, the members 9 and 10 in turn being integrally united with or otherwise permanently secured to the plate 11. Rivets 13 secure the plate 11 to another plate 14, which serves as a base upon which the bottom of the tubular container 1 is adapted to rest, and projecting upwardly from the base plate 14 are clamping lugs 15 and 16 55 which are adapted to grasp the annular member 3.

A screw 17 with a squared-off head 18 adapted to receive an ordinary skate-key, is received within the interiorly-threaded traveling boss 19. To said traveling boss 19 the slide 20 is secured, and at the left-hand end, Fig. 2, said slide 20 terminates in a clamping member 21. A lug 22, which may be formed integrally with or otherwise permanently secured to either the base plate 14 or the plate 11, depends downwardly and is perforated to receive the screw 17. The head or collar 23 is permanently secured upon said screw and normally engages the right-hand surface, Fig. 2, of the member 22. When the screw 17 is rotated in one direction, therefore, the slide 20 will be drawn toward the right, and the upwardly-projecting foot or clamping member 21 will be drawn tightly into engagement with the annular member 3, which said member 3 obviously will be clamped between the clamps 15, 16, and 21, and in this way the running gear will be secured to the bottom of the club-holding receptacle 1. When the screw 17 is turned in the opposite direction, however, the running gear is unclamped and may be removed from the tubular receptacle 1.

A strut or struts 24 are provided, same being preferably made of metal or the like and shaped as best shown in Fig. 1. Each strut 24 is provided with a pointed end 25 and near the point is a stop 26. The upper end of each strut 24 is bent into a hooklike form 27, which hook being made resiliently will clamp the annular member 2. The pointed end 25 can be driven into the ground, its downward movement obviously being limited by the stop 26, and in this way the struts 24 will hold the tubular bag 1 in the position depicted in Fig. 1 of the drawings.

To one of the plates 11 or 14 the upwardly-projecting strap 28 is secured, which strap at its upper end carries the ears 29 and 30. A lever 31 provided with a pointed end 32 is pivotally mounted upon the shaft or rod 33, which extends across the space between the ears 29 and 30. A spring 34 is riveted or bolted at 35 to the member 28 and said spring 34 engages and presses against the looplike end of the member 31 which encircles the rod or pintle 33. Adjacent the pointed end 32 is a stop 36 which limits the downward movement of the member 31 when its pointed end 32 is forced into

the ground as is done when the user desires to have the receptacle elevated and at rest. When the user wishes to move the receptacle from one place to another, however, the 5 member 31 is lifted out of the ground and is swung upwardly to the dotted line position, Fig. 1, in which position member 31 will be retained because of the frictional engagement therewith of the spring 34.

10 When the user of the receptacle is not moving around from place to place, the different parts assume the position shown in Fig. 1 of the drawings, but when the user wishes to move, the member 31 can be moved 15 from full line position to dotted line position, the struts 24 can be pulled out of the ground, and if so desired, removed from the position indicated in Fig. 1 and placed within the tubular container 1, which tubular 20 container can be wheeled upon its running gear to any desired place or position and

thence quickly set up again. Sundry changes in the details of construction may be made in an obvious manner without departing from the scope of the invention. 25

I claim as my invention:—

The combination with a golf club receptacle comprising an attenuated tubular member, of a wheeled standard secured to one end thereof, and means for maintaining 30 the receptacle substantially upright upon said standard comprising a forward removable strut clamped to the upper end of the receptacle and having a pointed lower end and an offset projection adjacent thereto, 35 and a rear strut horizontally pivoted to the standard, having a pointed free end for insertion in the ground and bearing a projection adjacent its point.

In testimony whereof I have affixed my 40 signature.

JENNIE KELLEY.
